UNITED STATES PATENT OFFICE.

ARTHUR PERCY STROHMEGER, OF WESTMINSTER, LONDON, ENGLAND, ASSIGNOR
TO SLAUGHTER AND COMPANY, LIMITED, OF LONDON, ENGLAND.

ELECTRIC DEPOSITION OF METALS BY FUSION.

1,073,543.

Specification of Letters Patent. Patented Sept. 16, 1913.

Application filed January 14, 1913. Serial No. 741,942. **REISSUED**

To all whom it may concern:

Be it known that I, ARTHUR PERCY STROHMEGER, a subject of the King of Great Britain, residing at Caxton House, Westminster, 5 London, England, have invented new and useful Improvements in the Electric Deposition of Metals by Fusion, of which the following is a specification.

This invention relates to processes in 10 which an electric current is employed to fuse a metal electrode so that the fused metal is deposited upon a metal surface or surfaces which are thereby welded or patched.

15 According to this invention the electrode which is coated with insulating material is pressed down upon the work by a weight or its equivalent so that throughout the process the bared end of the electrode is in contact with the work.

The electrode may be made in the shape of a bow or arch or may be straight in which case one end will be separated from the work by a distance piece.

20 25 The insulating material which I prefer to use is asbestos spun into the form of yarn and smeared with a suitable composition such as sodium silicate, aluminium silicate and the like to vary the fusing temperature of the yarn.

The accompanying drawing shows diagrammatically two methods of patching the worn head of a tramway rail.

25 Figure 1 shows the use of a straight electrode and Fig. 2 shows the use of a curved electrode.

In Fig. 1 the electrode formed of a strip

of metal *a* coated with insulating material *b* is connected to the positive pole of a source of direct current and is placed on the rail 40 *c* (which is connected to the negative pole) in an inclined position one end being supported by a block *d* while a weight *e* is placed on the strip. On the arc being started, the coating *b* which protects the 45 electrode and prevents the current jumping from the electrode to the work except at the arc, is fused at the arc and acts as a slag and the metal of the strip is deposited on the rail; the arc moves back along the strip, 50 the end of which is always pressed down toward the surface of the rail but is kept out of actual contact by the coating *b*.

In Fig. 2 instead of a straight strip supported on a block, a curved strip is shown. 55

What I claim is:—

A process of depositing metal by means of the electric arc, which comprises connecting the work to one pole of a source of electricity, placing above the line along which metal is to be deposited and at an angle to the work a metal electrode coated with insulating material adapted to act as a slag when fused, connecting this electrode to the other pole of the source of current, striking an arc between the work and the end of the electrode, and pressing this end of the electrode down on to the work throughout the continuance of the arc. 65

ARTHUR PERCY STROHMEGER.
